United States Patent Office

Des. 181,883
Patented Jan. 7, 1958

181,883

BALL POINT PEN OR SIMILAR ARTICLE

William S. Sherman, Chicago, Ill., assignor to Corry Corporation, Chicago, Ill., a corporation of Delaware

Application March 19, 1957, Serial No. 45,318

Term of patent 14 years

(Cl. D74—17)

FIG.1.

FIG.2.

FIG.3.

FIG.4.

Fig. 1 is a side elevational view of a ball point pen showing my new design;

Fig. 2 is a front elevational view;

Fig. 3 is an enlarged top plan view of the pen as shown in Fig. 1; and

Fig. 4 is an enlarged bottom plan view of the pen as shown in Fig. 2.

I claim:

The ornamental design for a ball point pen or similar article, substantially as shown.
